HEADLIGHT

Filed Oct. 31, 1930

UNITED STATES PATENT OFFICE

CONRAD K. RIZER, OF NEW YORK, N. Y.

HEADLIGHT

Application filed October 31, 1930. Serial No. 482,392.

My invention relates to improvements in headlights for automobiles or other vehicles, and constitutes a continuation in part of my pending application Serial No. 338,135, filed February 7, 1929.

This invention is particularly directed to a headlight reflector which will concentrate the direct light rays in a region below the direct line of vision of the driver of an approaching vehicle, and contemplates a reflector formed of conic curves in a definite relation to the light source to accomplish the desired result.

In addition to confining the direct rays to the stated region, my reflector will produce a uniformly lighted area on the highway immediately in front of the vehicle and extending a sufficient distance to permit safe driving.

Further objects and advantages will become apparent from the following description, taken in connection with the accompanying drawings, wherein:

Fig. 1 is a vertical sectional view through a reflector embodying my invention, particularly showing the distribution of the light rays;

Fig. 2, a top plan view;

Fig. 3, a rear view of Fig. 2;

Fig. 4, a top plan view of a modified form of reflector; and

Fig. 5, a rear view of Fig. 4.

Referring to the drawings, and more particularly to Figs. 1, 2 and 3, R designates generally a headlight reflector constructed in accordance with my invention and comprising conic curves so arranged and related with respect to a light source 2 as to produce the desired distribution of light rays emanating therefrom. The reflector R may be formed of any suitable material, as for example sheet metal, the inner surface of which is adapted to the application of a reflecting plating or coating.

The generation of my reflecting surface may be more readily understood by a reference to a regular system of axes X—X, Y—Y, and Z—Z, passing through the light source 2 and having a common origin O coincident with the filament of said light

source. A parabolic arc 3 is disposed in the plane X—Y having its vertex *a* forwardly of the light source 2 and its latus rectum BD coincident with the transverse axis X—X, thereby coinciding the focus of 55 the parabolic arc 3 and the origin O.

Said parabolic arc 3 is revolved about its latus rectum BD in such a manner that its vertex *a* describes a hyperbolic spiral in the plane Y—Z, a portion of such spiral being 60 shown from *a* to *b* in Fig. 1.

As the said arc 3 rotates, it continuously increases in size, accompanied by a corresponding increase in the focal length, until at the point *b* on the spiral, the arc has become 65 the arc 3' of Fig. 2 having a focal distance *Ob*, and the latus rectum has increased to the value EF along the axis X—X. The radius vector of the hyperbolic spiral and the focal distance of said arc are equal and coincident throughout the spiral portion *a*—*b*.

It will readily be seen that if this rotation is continued the latus rectum of the parabolic arc will increase beyond a practical value, that is to say, the reflector will become extremely wide. Therefore, some limiting value GH of the latus rectum may be selected as a maximum width of the reflector, said value occurring when the vertex *a* of the parabolic arc 3 has been rotated to the 80 point A on the hyperbolic spiral.

To complete the reflecting surface, the parabolic arc 3 is further rotated about the axis X—X with the vertex of said arc continuing along the hyperbolic spiral from A 85 to *c*, or until the arc again intersects the plane XY, said parabolic arc being designated 3" in Fig. 2. That is to say, the arc 3 rotates through an angle of 360 degrees from *a* to *c* to complete the reflecting surface. During this latter rotation, the maximum width of the parabola is maintained constant and equal to GH. Therefore, although the radius vector of the hyperbolic spiral is continuously increasing to a maximum at the point *c*, the focal distance of the parabolic arc decreases and the focus thereof continuously moves away from the light source 2.

In the form of Figs. 4 and 5, I have 100

shown a reflector designated R', wherein the focal distance of the parabolic arc 3 and the radius vector of the hyperbolic spiral $a-b-A-c$ continuously increase together 5 from a to c , whereby the focus of said arc is maintained coincident with the light source throughout the generation of the entire reflecting surface. The value GH of the latus rectum of the parabolic arc 3 is 10 again taken as the maximum width of the reflector, but the reflecting surface from A to c formed by the continued rotation of the increasing arc 3 about its latus rectum is limited by its intersection with vertically extending side portions 4.

Thus, the reflectors R and R' are the same in vertical cross section, and the generation of their surfaces from a to A along the hyperbolic spiral is the same, whereby both 20 of the reflectors are provided with reflecting surface about the light source 2 formed by the rotation of the increasing parabolic arc 3 about its latus rectum passed through the light source. Such surface will provide a 25 concentration of light rays at 5 in Fig. 1, for illuminating the highway some distance ahead of the vehicle to which the reflector may be applied. In addition, the much larger extended and broader reflecting surface from A to c will produce a diffused illumination of the area immediately in front and below the reflector, as at 6.

The distribution of light rays in a horizontal direction will produce an evenly distributed area of concentrated rays in the region 5, due to the parallel reflection of the surface bA of the reflector, and a widened area of diffused light 6 from the portion Ac .

However, in the form of Figs. 4 and 5, the 40 diffused lighting at 6 will also be in the form of parallel light due to the fact that the reflecting surface Ac is generated by a parabolic arc revolved about its latus rectum which passes through the light source.

The reflectors R or R' may be mounted 45 on a vehicle in any suitable manner. As shown in Fig. 1, the longitudinal Y-Y axis of the reflector is inclined at a slight angle to the horizontal, permitting a greater 50 range of illumination. However, it will become evident that no direct rays of light from the source 2 will come within the vision of an approaching driver, all harmful rays being cut off and deflected downward 55 by the reflector portion Ac . The reflector may be enclosed in a pivotally mounted casting, to permit adjustment of the inclination thereof.

Various changes and modifications are 60 contemplated provided they fall within the scope of the following claims.

I claim:

1. A light reflector of the character specified having a reflecting surface generated 65 by the rotation of a continuously increasing

parabolic arc in such a manner that the vertex of said arc describes a spiral.

2. A light reflector of the character specified having a reflecting surface generated by the rotation of a continuously increasing 70 parabolic arc in such a manner that the vertex of said arc describes a spiral, the radius vector of the spiral and the focal distance of the arc being equal and coincident throughout a portion of the spiral. 75

3. A light reflector of the character specified having a reflecting surface, a portion of which is generated by the rotation of a continuously increasing parabolic arc about its latus rectum in such a manner that the 80 vertex of said arc describes a spiral.

4. A light reflector of the character specified having a reflecting surface, a portion of which is generated by the rotation of a continuously increasing parabolic arc about its 85 latus rectum passed through the light source, in such a manner that the vertex of said arc describes a spiral.

5. A light reflector of the character specified having a reflecting surface generated by 90 the rotation of a continuously increasing parabolic arc through a complete revolution about its latus rectum in such a manner that the vertex of said arc describes a spiral.

6. A light reflector of the character specified having a reflecting surface generated by 95 the rotation of a continuously increasing parabolic arc through a complete revolution about its latus rectum passed through the light source, in such a manner that the vertex of said arc describes a spiral. 100

In testimony whereof I affix my signature.
